GAME WITH SCORE RECORDING MECHANISM
Vincent C. Engstrom, South Gate, Calif., assignor to
Arthur Looff and Etta M. Looff, jointly, both of Long
Beach, Calif.

Filed Oct. 17, 1966, Ser. No. 587,175
8 Claims. (Cl. 273—124)

The present invention relates generally to the field of commercial amusement devices, and more particularly to an improvement in the score recording mechanism utilized in a ball-actuated game. The game is of the type in which a plurality thereof are arranged in a bank, with each player endeavoring to secure a winning score.

Games of the type described are normally operated by paid employees, who in most instances collect the charge for each game from the player prior to the start of play. In the event an employee does not account to an owner for all monies collected from the participants of the games, the revenue lost to the owner thereof can be substantial over a period of time.

Heretofore no accurate and automatic means have been devised by which the owner of such games may determine the number of games that have been played, and the amount of money his employees should have collected over a particular period of time therefor. Also, prior to the present invention the previously available games were not provided with means for signalling to a player that his particular game apparatus was operative, rather than inoperative due to mechanical or electrical malfunctioning thereof.

One of the operational disadvantages of the previously available ball-actuated games of the type described has been that the contact points in switches used in the electrical circuits thereof oxidize and corrode when exposed to damp air and moisture, whereby one or more games in a bank thereof may become inoperative. Normally, such inoperative games cannot be repaired when the balance of the games in a bank are in use, and as a result, the owner thereof suffers a substantial loss in revenue.

A major object of the present invention is to provide an improvement in commercially operated, ball-actuated amusement devices, which minimizes the period the games are inoperative, with the improvement being adapted to be incorporated in either new or old game devices.

Another object of the invention is to supply an improvement for use in ball-actuated games by means of which the number of times each game in a bank is automatically and accurately recorded.

A still further object of the invention is to provide an improved game apparatus which is adapted to be used in a bank of ball-actuated games, that will visually signal to each player whether his particular game is operative the first time the ball associated therewith passes through an opening in the playing surface of the game apparatus.

Yet a further object of the invention is to provide improvements in ball-actuated games which not only accrue to the benefit of the owner, but the players thereof as well.

These and other objects and advantages of the invention will become apparent from the following description thereof, and from the accompanying drawings illustrating the same, in which:

FIGURE 1 is a plan view of a game board or playing field, a portion of which is broken away to show a part of the pivotally supported levers thereunder, that are adapted to be actuated when a ball passes through openings in the game board;

2

FIGURE 2 is a plan view of the score recording mechanism per se;

FIGURE 3 is a fragmentary longitudinal cross-sectional view of the apparatus shown, FIGURE 2, taken on the line 3—3 thereof;

FIGURE 4 is a second fragmentary, longitudinal cross-sectional view of the recording mechanism shown in FIGURE 2, taken on the line 4—4 thereof;

FIGURE 5 is a vertical cross-sectional view of the recording mechanism, taken on the line 5—5 of FIGURE 3;

FIGURE 6 is a plan view of the recording mechanism after a winning score has been secured;

FIGURE 7 is an end elevational view of a portion of the game, illustrating the condition thereof prior to play;

FIGURE 8 is the same end elevational view of the game apparatus shown in FIGURE 7, after operation thereof;

FIGURE 9 is a vertical cross-sectional view of the game apparatus, taken on the line 9—9 of FIGURE 8;

FIGURE 10 is an enlarged perspective view of a portion of the apparatus indicated by the numeral 10 in FIGURE 8; and

FIGURE 11 is a longitudinal cross-sectional view of one of the electric switches used with the score recording mechanisms.

With continued reference to the drawings for the general arrangement of the improvement in the score recording mechanisms for a game apparatus, it will be seen that each such mechanism is operatively associated with a game board, frequently referred to as a "pin ball" type.

The game apparatus includes a playing field 10, as best seen in FIGURE 1, in which a number of holes are formed through which a ball or marble may drop, and this playing field is customarily covered by a sheet of glass or other transparent material. The object of the game is to obtain scores by causing the ball to drop in one or more holes or certain combinations of holes. Two or more players on separate game boards can play competitively, with the winner being the first to complete certain plays or make certain scores. In the form illustrated herein, the scoring holes are arranged in two rows, 11 and 12 extending from right to left across the playing field 10.

In order to play one of the games, a player retracts plunger 13, and then allows the plunger to suddenly move forward under the influence of a spring (not shown). The plunger drives ball 14 forwardly and upwardly along inclined ramp 15 and against a curved guide 16 which directs the ball onto the rear upper end of the playing field 10. Field 10 is slightly inclined downwardly and forwardly toward the player whereby ball 14 rolls down it toward the scoring hole due to the force of gravity.

A number of bumpers or posts 17 are provided in order to make it more difficult to drop ball 14 through any particular scoring hole in the rows 11 and 12. If ball 14 does not drop through any of the holes in rows 11 and 12, it will strike against a guide 18 which directs the ball into the non-scoring hole 19.

After ball 14 drops through any of the holes in playing field 10 it eventually drops onto the inclined surface 20, which is located beneath the playing field 10. The balls roll downwardly on surface 20 onto a track 21. A curb 22 is parallel to track 21 at its lower edge, and the track and curb direct the ball downwardly and to the right to return it to the position shown immediately in front of plunger 13, from which it may be again played by the operator.

The recording mechanism comprises an open, rectangular frame 24 on which is mounted a plurality of parallel levers, indicated collectively by the numeral 25. These levers 25 are further individually distinguished by the numerals 26-50 inclusive, except that there is no lever 38 for reasons which will be explained hereinafter. All levers 25 are pivotally mounted in a row on a horizontally extending rod 52 secured to the side wall 24a, as can best be seen in FIGURE 2, by transversely apertured screws 52a. Levers 25 pivot in a vertical plane, and are guided by slots 24e provided in the rear side wall 24b, as shown in FIGURE 9. There is one lever 25 for each scoring hole in rows 11 and 12 on the playing field 10.

The even numbered levers are shorter in length than the odd numbered levers to permit positioning of the ends of the even numbered levers under the scoring holes in rows 11 as illustrated in FIGURE 1. The forward end portions of the odd numbered levers are positioned beneath the scoring holes in row 12.

Frame 24 is supported on a pair of elongate longitudinally extending members 53 which project rearwardly beyond frame 24. Members 52 support a cross bar 54 of L-shaped transverse cross section, as may best be seen in FIGURES 2 and 8. A number of electrical switches 55 are supported on cross bar 50, which extend forwardly therefrom. The switches 55 are disposed in side-by-side relationship, as shown in FIGURE 2. The same number of switches 55 are provided as levers 25, and the switches are so located that one switch is associated with, and operated by a lever.

Levers 25 are individually biased towards a horizontal position, or one that is nearly so, as may be seen in FIGURES 7 and 10, by a number of springs 25b secured to a transverse member 25c affixed to side wall 24a by conventional means. An inverted U-shaped hook 25d is formed on the free end of each spring 25b, and this hook engages the forward portion of one of the levers 25.

The construction of one of the switches 55 is shown in FIGURE 11, each of which includes a rectangular base 55a formed of an electrical insulating material such as plastic or the like, which is impervious to moisture, and is provided with a first contact 55b mounted on the upper surface thereof. Contact 55b is connected to a first terminal 55c that extends downwardly through base 55a. A second terminal 55d extends through base 55a, and holds an elongate electrical conducting toggle assembly 55e in longitudinally spaced position on the upper surface thereof. Toggle assembly 55e includes a second contact 55f that is in engagement with contact 55b when a force is not exerted on the right-hand portion of the assembly, as is illustrated in FIGURE 11.

An inverted elongate cap 55g formed of a moisture impervious, electrical insulating material is mounted on the upper portion of base 55a, which cap slidably supports a vertically movable pin 55h. Pin 55h rests on the upper left-hand portion of assembly 55e. An elongate rigid actuating member 55i is pivotally supported by a transverse pin 55k above cap 55g. The ends of pin 55k are supported by two transversely spaced, upwardly extending lugs 55e that are integral parts of cap 55g.

Terminals 55c and 55d are electrically connected when actuating member 55j is in the upwardly extending second position shown in FIGURE 11. When member 55j is pivoted in a counter clockwise direction (FIGURE 11) to a first position substantially parallel to the upper surface of cap 55g, the contacts 55c and 55d are separated by pin 55h as it is moved downwardly to exert a force on the upper portion of assembly 55e.

As indicated in FIGURES 6-8 inclusive, the terminals 55d are connected to a common wire 56 that extends to a suitable source of power. The other terminals 55c are connected to a common wire 56a extending to said source, as well as to a number of signal lights 57.

It will thus be seen that the number of signal lights 57 is equal to the number of scoring holes on playing

field 10, with there being one light representing each hole whereby when a score is made by dropping a ball through that hole, the corresponding light may be lit to visually indicate that a score had been made. A light 57, but without a switch 55 in its circuit, is ordinarily provided to represent hold 38. All signal lights 57 are normally located on a scoreboard or annunciator, which may be located at the back end of playing field 10, or is frequently located a short distance away from the game board.

10 A plurality of transversely extending bars 60 are slidably mounted in end members 24c and 24d of frame 24. These bars are identified collectively by the numeral 60, but are given individual numerals 62-72 inclusive, as best seen in FIGURES 1 and 6. These bars are spring-biased 15 toward the right as illustrated in FIGURE 1 by springs 75 (FIGURE 9) which are under tension, and attached one to each of the bars 62-72 inclusive, as well as to transverse rigid rods 76a that extend between side walls 24a and 24b.

The transverse bars 60 are held against horizontal sliding movement toward the right, as shown in FIGURE 1, by engagement with one or more of the levers 25. As will be more fully explained hereinafter, each transverse bar 60 initially engages each lever of a group of levers 25, and when play has proceeded in such a way that all levers of that group are tilted to indicate scores, that bar is then disengaged by the levers and is free to move as a result of a force applied to the bar by the spring 75 attached thereto.

30 To engage levers 25, each of the bars 60 is provided at appropriate locations with a plurality of stops 76, which project above the top surfaces of the bars a short distance in order to engage the side face of levers 25 when the levers are in the horizontal or normal position shown in FIGURE 7. Any other suitable means of engaging the transverse bars 60 and levers 25 may be used; for example, it is possible to form the bars with notches or irregularities in the upper edges thereof which will engage the levers 25.

40 After a lever 25 has been struck by a ball as it drops through a scoring hole, it is tilted to the position shown in FIGURE 8 wherein it closes a switch 55 associated therewith. It is then desirable to maintain the lever 25 in this position in order to keep switch 55 closed and signal light 57 illuminated. For this purpose means is provided which is adapted to hold each individual lever 25 in the tilted position.

Such means is shown best in FIGURES 3 and 5, and comprises a plurality of holding member 78 pivotally mounted on a fixed bar 79 that extends between end walls 24c and 24d. There is one such member 78 for each lever 25 (FIGURE 3). Normally, holding members 78 are substantially vertical, and press against the side of the associated lever 25 in the manner shown by the two right-hand members 78 illustrated in FIGURE 3. Spring wires 80 attached to the lower end of holding members 78 and to the rear side wall 24b, urge the holding members to pivot in a counter clockwise direction as shown. Consequently, as soon as the rear end of any lever 25 is raised, the associated holding member 78 swings into the path of that lever and prevents the lever from dropping back into the position it normally occupies, which is shown in FIGURE 7. In FIGURE 3 levers 26, 27 and 28 are shown held in the tilted position by holding members 78. Pivotal movement of members 78 is limited by stops 82 which extend horizontally from a transverse bar 83 that is slidably mounted in the end members 24c and 24d of frame 24.

70 At the right-hand end of frame 24 a U-shaped bracket is mounted, and between the outstanding arms of this bracket, a plate 87 is pivotally mounted on a shaft 86 in a position opposite to the right-hand ends of all transverse bars 60, as illustrated in FIGURE 2. A projecting portion 88 of plate 87 is in a position to engage

the free ends of an actuating member 89 of a normally open electrical switch 90. When the plate 87 is disposed as shown in FIGURE 2 it holds a switch 90 in an open position. Also, when any one of the bars 60 moves to the right, as illustrated by bar 62 in FIGURE 6, the right-hand end of the bar engages the pivotal plate 87 to swing the upper end thereof outwardly.

This movement of plate 87 causes projection 88 into pressure contact with the actuating member 89 to close switch 90 (FIGURE 6). One contact of switch 90 is connected to wire 56, which is a common source of electrical current. When switch 90 is closed, it also closes a circuit to a signal light 91, shown in FIGURES 7 and 8, which light is normally in a position adjacent to signal lights 57. Usually light 91 is of a different character than lights 57, and is used to indicate that a winning play has been made. In addition to a visual light signal, an audible signal may be utilized by incorporating suitable equipment in the electrical circuit.

Plate 87 is also used as a re-set mechanism to return any of the bars 60 which have moved to the right to their normal positions, and movement of bar 83 serves the same purpose relative to the holding members 78. For this purpose a bell crank 93 is pivotally mounted on shaft 86 that extends from a bracket 85, as seen in FIGURE 8. The upwardly extending arm of crank 93 is provided with a projection that is engageable with plate 87 (FIGURE 9). The horizontal arm of bell crank 93 is provided with a pull cord 95, or other suitable means, whereby the crank may be turned about on its pivotal mounting.

A generally U-shaped bail 100 is provided, as shown in FIGURE 2, that includes two parallel arms 101, connected by a web 102. The free ends of arms 101 are bent to define two prongs 103 that extend towards one another, and are pivotally supported in two longitudinally aligned openings formed in end pieces 24c and 24d as also shown in FIGURE 2. Bail 100 is preferably formed from a stiff wire. The web 102 rests on the upper edges of the rear portions of levers 25, and these lever portions project beyond the side wall 24b, as may best be seen in FIGURES 2 and 6-9 inclusive.

An electric switch 105 is mounted on the rear portion of one of frame support members 53 as shown in FIGURES 2, 7 and 8. Switch 105 includes a pivotally movable, forwardly extending spring-loaded actuating member 106, and it is in the open position when the actuating member is substantially horizontal as shown in FIGURE 7. Due to the spring-loading thereof member 106 tends to pivot upwardly, but is restrained from so doing by bail 100 with which it comes into contact. However, when bail 100 is pivoted upwardly to the position shown in FIGURE 8, member 106 pivots upwardly and places switch 105 in a closed position.

One terminal of switch 105 is connected by a conductor 107 to a source of power. Two other terminals of switch 105 are connected to a signal light 108 and an electrically actuated counter 109 by conductors 110 and 111 respectively, which are also connected to the source of electric power (not shown).

The operation of the game apparatus of the present invention is as follows. The player causes ball 14 to drop through one of the scoring holes in rows 11 and 12, and strikes the forward end of a lever 25 located directly beneath said hole to tilt the lever. Thus the impact of the falling ball causes a lever 25 to move from its normal position shown in FIGURE 7 to the tilted position illustrated in FIGURE 8, whereby the raised rear end of the lever allows the actuating member 55j of the associated switch 55 to pivot upwardly into the closed position. Closing of this particular switch 55 results in illumination of the specific signal light 57 associated with that opening in rows 11 or 12 through which the ball has passed.

The first lever 25 to pivot from the position shown in FIGURE 7 to that illustrated in FIGURE 8 results in

movement of bail 100 to the tilted position shown. Pivoting of bail 100 to this position allows an actuating member 106 to pivot upwardly and close switch 105. When switch 105 is closed, a circuit is completed to signal light 108 to indicate to the player that the game is in an operative condition, but also energizes counter 109. Each time the counter 109 is energized, the cumulative visual total thereon (not shown) is increased by another unit. Counter 109 is of conventional design.

In the normal or initial position of each lever 25, a pivoted holding member 78 bears lightly against one side of the lever in the manner shown by the two right-hand members 78 in FIGURE 6. When lever 25 is tilted to raise its rear end, the holding member 78 associated therewith swings about its pivot on bar 79 to move underneath lever 25, as shown by the two right-hand members 78 in FIGURE 3. Each member 78 holds each lever 25 in its tilted position, and each switch 55 associated with each lever is held closed so that a signal light 57 remains illuminated.

It will be understood that the purpose of the game apparatus of the present invention, as is ordinarily the case with games of this type, is to attain scores by causing a ball or marble used therewith to drop through certain selected holes. In this particular instance, the object is to obtain scores by causing the ball to drop through all the scoring holes of a particular group. Characteristic of the manner in which groups of holes may be established or predetermined without the necessity of limitation thereof, twenty-four levers 26 to 50 inclusive are arranged one beneath each one of an equal number of scoring holes, with the holes and levers being arranged in a predetermined number of groups of five each.

The first five groups of levers 25 are determined by designating each successive five levers, starting from either end of the row as seen in FIGURE 2, as a group, except that the center group includes only four levers, although there are five scoring holes in this group. This situation is due to the fact that there is no lever beneath scoring hole 38. This construction illustrates the so-called "free play" in which the player is automatically credited with a score equivalent to that represented by hole 38, without actually having to drop a ball 14 therethrough. Since in this particular game, it is not possible to obtain another score by causing a ball to drop through a specific hole a second time, the lever beneath the free-play hole 38 has been omitted.

It will be understood that in the event a game is played in which a repeat score can be obtained, then a lever underneath hole 38 may be added, just as are the other levers. Because of the presence of hole 38 on playing field 10, levers 25 are grouped by fives as if there were a lever beneath hole 38, making a total of twenty-five, but for other purposes, hole 38 may be considered as a non-scoring hole.

According to this grouping of levers 25, it will be appreciated that the first group consists of levers 26, 27, 28, 29 and 30. The second group consists of levers 31-35, the third group of levers 36-40, the fourth group, levers 41-45, and the fifth group, levers 46-50.

As a consequence of this grouping of levers, bar 62 is provided with five stops 76. Stops 76 are spaced along the transverse bar 62 in the same intervals as successive levers 25, and are so located that one stop engages each lever 26, 27, 28, 29 and 30, as shown particularly in FIGURE 2. It will be understood that as long as levers 25 are in their normal positions, each stop 76 on bar 61 engages a lever of the first group of five levers.

Assuming play has progressed to the point where only levers 26, 27 and 28 have been moved to the tilted position, the component parts thereof occupy the positions illustrated in FIGURES 3 and 4. Holding members 78 will have moved to retain levers 26, 27 and 28 in the tilted position whereby these three levers maintain their associated switches 55 in a closed position. Also, these

three levers will have disengaged stops 76 on bar 61, but the bar is still prevented from transverse movement to the right due to engagement of two stops 76 with levers 29 and 30. When play has progressed further and levers 29 and 30 have been moved into the tilted position, bar 62 is then disengaged from each lever of the first group and thereafter moved to the right by the attached spring 75.

When bar 62 slides to the right, the end thereof engages plate 87 and causes the plate to swing about the shaft 86, thus bringing projection 88 into pressure contact with actuating member 89 of switch 90 and closing the switch (FIGURE 6). This action closes the electric circuit to signal light 91, which signals that a winning play has been made as a result of the player having completed the necessary scores.

From the above description and an inspection of FIGURE 2 it will be seen that any one of the bars 62-72 may move to the right after the ball 14 has passed through a particular group of openings in rows 11 or 12. Movement of any one of the bars 62-72 to the right is sufficient to close switch 90 to signal that a winning score has been secured.

After a winning play has been completed, it is then necessary to restore the parts of the mechanism to their original positions in order that a new game may be commenced. This restoration of the various parts of the game apparatus is accomplished primarily by actuation of bell crank 93. At the end of play, the component parts may be in the positions shown in FIGURE 6 in which bar 62 is bearing against plate 87.

Upward motion of the bell crank is limited by a stationary pin 97. In order to reset the mechanism, cord 95 is drawn downwardly, causing the bell crank to rotate in a clockwise direction to the position shown in FIGURE 9. This motion brings a projection 94 provided on bell crank 94 into engagement with plate 87, and also causes the latter to rotate in a clockwise direction about shaft 86. Plate 87 engages the ends of any and all transverse bars 60 which may have moved from their initial positions shown in FIGURE 2. Continued movement of plate 87 moves the transverse bars to the left (FIGURE 2) until the ends are nearly flush with frame 24. At this point the bars 60 will have been moved sufficiently to the left that the stops 76 have been moved to clear levers 25, and accordingly are in a position to re-engage levers 25 when these levers are dropped back into their normal positions.

As bars 60 move, bar 83 is engaged by plate 87 and moved to the left. Each of the spaced stops 82 carried on bar 83 engages a pivotal member 78 and rotates these members in a counter clockwise direction, as illustrated in FIGURE 3, about its pivotal mounting on bar 79. This movement is in direct opposition to that caused by springs 80. As seen in FIGURE 3, the top ends of all holding members 78 are moved to the left, out of the path of levers 25, whereby these levers are thus free to drop back into the horizontal position shown in FIGURE 7 under the influence of springs 25b. This action permits the switches 55 to return to their open position and break all the electrical circuits to the signal lights 57.

When the levers 25 are moved from the position shown in FIGURE 8 to that illustrated in FIGURE 7, the bail 100 pivots downwardly by force of gravity and the switch 105 is placed in the open position. The electrical circuit to the signal light 108 and electrically operated counter 109 is then broken.

After the bell crank 93 has been moved downwardly to the fullest extent and all of the transverse bars 60 and 83 are moved to the left, travel of these bars preferably carries them somewhat beyond their position of rest which they occupy at the commencement of play. This is done in order that stops 76 and holding members 78 may be moved entirely clear of levers 25. When levers 25 have been returned to their normal position by springs 25b they are then in place for engagement by stops 76 and 75.

holding members 78, for the transverse bars 60 and 83 are moved slightly towards the right by springs 75 and the bell crank 93 released to be returned by a spring 98 to engage the stationary pin 97.

Plate 87 is preferably biased either by force of gravity or a spring towards the ends of the transverse bars in order that it does not prematurely engage the electric switch 90. It will thus be seen that the bars 60 and 83 and levers 25 as well as bail 100 are all simultaneously returned to their original positions as a result of the movements which occur upon actuation of the bell crank 93 and plate 87.

Although the present invention is fully capable of achieving the objects and providing the advantages hereinbefore mentioned, it is to be understood that it is merely illustrative of the presently preferred embodiment thereof, and I do not mean to be limited to the details of construction herein shown and described, other than as defined in the appended claims.

I claim:

1. In a score recording mechanism for use with a game apparatus having a plurality of parallel, laterally spaced levers pivotally supported from a rectangular open frame and projecting forwardly therefrom, which levers are located below a playing surface and have spaced openings formed therein through which a ball drops to sequentially tilt said levers, a plurality of bars slidably supported on said frame with each bar being engageable by a predetermined group of levers, first means for moving each of said bars when said group of levers associated therewith are tilted to be disengaged therefrom, a normally open electrical circuit, a plurality of signal lights and an electrically operable game win-indicating device connected to said circuit, a first normally open switch forming a part of said circuit that is closed by the movement of one of said bars to complete said circuit to said game win-indicating device, the improvement for operation of said game apparatus, comprising:

(a) a plurality of normally open second electric switches associated with said levers and connected to said circuit and signal lights, each of which second switches include means to protect the contact points thereof from corrosion, with each of said second switches when closed by the tilting of said associated lever completing said circuit to one of said signal lights to indicate the progress being made in securing a winning score;

(b) second electrically operable means, which when energized, indicate said game is in an operative condition;

(c) third electrically operable counter means for maintaining a record of the number of times said game is played;

(d) a third normally open electrical switch, which when closed, completes said circuit to said second and third means, and

(e) fourth means for closing said third switch when said fourth means moves from a first to a second position, with said fourth means being moved to said second position by any one of said levers as tilted.

2. The improvement as defined in claim 1 wherein said means to protect said contact points comprises a hollow body impervious to moisture in which they are contained.

3. The improvement as defined in claim 1 wherein said second means is an incandescent bulb.

4. The improvement as defined in claim 1 wherein said counter maintains a visual total of the number of times said game is played, which total is increased by one unit each time said counter is electrically energized.

5. The improvement as defined in claim 1 wherein said third switch includes a spring-loaded actuating arm that at all times tends to move from an open to a closed position, and said fourth means comprises a member

movably supported from said frame and rests on all of said levers.

6. The improvement as defined in claim 5 wherein said fourth means comprise a bail pivotally supported from said frame, which bail is in pressure contact with said actuating member when any one of said levers first moves to a tilted position.

7. The improvement as defined in claim 6 wherein said bail is at all times resting on at least one of said levers.

8. The improvement as defined in claim 1 which further includes:

(f) spring means that all times tend to maintain said levers in a non-tilted position.
